UNITED STATES PATENT OFFICE.

EDWARD C. CORADO, OF WINNIPEG, MANITOBA, CANADA.

HYDROCARBON BURNER.

1,404,343.

Specification of Letters Patent. Patented Jan. 24, 1922.

Application filed April 15, 1920. Serial No. 374,225.

To all whom it may concern:

Be it known that I, EDWARD C. CORADO, of the city of Winnipeg, Province of Manitoba, Dominion of Canada, a subject of the King of Great Britain, have invented certain new and useful Improvements in Hydrocarbon Burners; and I do hereby declare that the following is a full, clear, and exact description thereof.

10 Heretofore in lamps of this type it has been necessary when snuffing the wick, or in other words, removing the accumulation of carbon therefrom, to "open up" the lamp.

This involves considerable labor, particularly in switch lamps as each lamp must be removed from its bracket and extinguished before its wick can be snuffed. The primary object of my invention is to overcome these disadvantages and to this end I have produced a burner having incorporated therein means for snuffing the wick which may be operated without disturbing the lamp in any way.

25 Further objects of my invention are to provide a simple and compact burner in which better combustion will be obtained, and in which the accumulation of gases in the base thereof with consequent overheating will be prevented.

30 To this end my invention consists of the particular construction and arrangement of parts hereinafter described and pointed out in the claims.

35 For full comprehension, however, of my invention reference must be had to the accompanying drawings in which similar reference characters indicate the same parts, and wherein:

40 Figure 1 is a side elevation partly in section of a burner constructed according to my invention;

Figure 2 is a horizontal sectional view taken on line 2—2 Figure 1;

45 Figure 3 is a vertical sectional view taken on line 3—3 Figure 2;

Figure 4 is a vertical sectional view taken on line 4—4 Figure 2;

Figure 5 is a detail elevation of the burner cap removed;

50 Figure 6 is a view similar to Figure 2 and illustrating a modification of my invention; and

Figure 7 is a detail fragmentary sectional view of the telescoped portion of the wick shaft.

A burner illustrating the preferred embodiment of my invention is shown in the accompanying drawings and consists of a body constituted by a base portion and a cap detachably mounted thereon, a combined means for feeding the wick and for snuffing the same, and a detachable chimney supporting bracket.

The base contains a chamber 4 which is enclosed by a surrounding side wall 5, bottom 6, and top 7, the lower end of the base being reduced and screw-threaded as at 8 for connection to the oil font a portion of which is indicated at 9. The wick tube 10 is of rectangular cross-section and extends from a central opening in the bottom to a short distance above the top.

In order to prevent the accumulation of gases within the chamber 4 and the font with consequent overheating the bottom is provided with openings 12 and the side wall with a circumferential series of openings 13 communication being thereby effected between the interior of the font and the atmosphere.

The burner cap is indicated at 15 and consists of a member of substantially hemispherical form the rim of which is curved in the form of a bead as indicated at 16. It is provided with the usual flame exit slot 17. To detachably fasten the cap upon the base, the top of the latter is circumferentially flanged as at 18 with upturned lips 19 and 20 curved to receive the bead 16, the flange being extended laterally as at 21 at a point diametrically opposite these lips and provided with a slot 22. This slot accommodates the free end of a spring clip 23 of U-form riveted to the under side of the extension as at 24 and constructed and arranged to engage the bead 16 on the cap, the extreme end of the clip being bent out at an angle as at 25 to provide a thumb-hold when releasing the cap.

The wick feeding means consists of the usual sprocket wheel 30 mounted upon a shaft 31 fixed against axial movement and extending across the chamber 4 and journalled in the side wall 5 thereof. This wick feeding means may or may not be combined with the snuffing mechanism, as illustrated in Figures 1 and 6. I find it preferable to employ the wick-feeding shaft 31 as a means for operating the snuffer to be hereinafter described and to this end the operating end

of the shaft is provided with a telescope extension 32 the outer end of which has the usual finger hold 33.

Approximately half the length of this section is of sleeve form as indicated at 34 the sleeve enclosing the outer end of the shaft 31 and relative displacement therebetween being prevented by a pin 35 on the latter moving in a slot 36 in the former.

10 The snuffer proper is mounted within the burner cap 15 and detachable therewith while the means for actuating it is carried by the burner base.

The snuffer proper consists of a member 15 40 of inverted cup form similar to that of the burner cap. This member is more than a snuffer as it assists in maintaining the equilibrium of the shaft. I will therefore refer to this member as the inside cap, the 20 burner cap, as hereinbefore stated, being the outside cap. This inside cap is fulcrumed within the same upon trunnions 41 journaled in openings 42, the trunnions being constituted by the outwardly bent ends of a 25 wire 43 of U-form fitted within the inside cap with the ends projecting through openings therein. A lip 44 secures the wire at its middle to the cap.

The inside cap is provided with an elongated opening or slot 45 in vertical alignment with the flame opening in the outside cap and bridged by a snuffing strip 46 constructed and arranged to directly act upon the top of the wick, the portion of the 30 opening normally located beneath the opening in the cap constituting a flame opening and the remaining portion a secondary opening 46'. The inside cap is so positioned relatively to the top of the wick tube and 35 the burner cap that the portion overhanging the former will be located half-way between the same and the top of the burner cap thereby establishing the equilibrium of the shaft hereinbefore referred to.

40 45 The means for actuating the inside cap consists of a push-rod 50 extending across the top of the burner base and moving in guides 51 formed integrally therewith and through notches 90 in the bead 16 of the 50 burner cap. This rod carries a forked device 52 between the arms of which a lever 53 on the cap projects, the arms being constructed and arranged to engage the lever and cause the inside cap to oscillate when 55 a thrust is exerted upon the push-rod.

The latter is operatively connected to the telescopic section of the wick feeding shaft by an oblong disc 60 mounted upon the end of the push-rod and encircling the telescopic 60 section between collars 61 but permitting the rotation of the same.

A helical spring 62 encircles the shaft 31 between a pin 62' projecting therethrough and a seat 63 at the mouth of the sleeve 65 which is of increased diameter. This spring

yieldingly maintains the inside cap in position with the flame opening 45 in vertical alignment with the flame opening in the cap.

The latter is provided with four air inlet 70 openings 70 of semicircular form located two on each side of the vertical axial flame of the trunnions 41 and adjacent the bead 16, and an opening 71 on each side of the flame opening and above the first mentioned openings.

In snuffing the wick of a lamp in use, the lamp tender has but to push inwardly on the telescopic section 32, the outer end of which is located outside the lamps. This 80 action, through push-rod 50, fork 52 and lever 53, oscillates the inside cap on its trunnions thereby moving the snuffing strip 46 across the top of the wick. As the telescopic section is relieved of pressure the spring 62 85 causes it to return to its initial position moving the push-rod and snuffer with it. This operation may be repeated as often as it is required to remove the carbon accumulation on the wick. Rotation of the wick shaft 90 does not affect the inside cap in any way.

With my improved construction and arrangement of parts the lamp tender is able to take full advantage of the capacity of the oil font which in railway switch lamps is 95 sufficient to last four or five days in that he does not have to open up the lamp until the font needs filling.

In the modification illustrated in Figure 6 the push-rod 50 is not connected to the 100 telescopic section of the wick-shaft and the spring 62 is transferred from the latter to the push-rod.

What I claim is as follows:—

1. In a hydrocarbon burner the combination 105 with the wick; of combined means for feeding the wick and snuffing the same said means including a sprocket for engagement with the wick, a snuffing device located in a position adjacent the upper end of the wick 110 and movable transversely thereto and means capable of rotary and axial movement and operatively connected to the sprocket and said snuffing device.

2. In a hydrocarbon burner, the combination 115 with the body thereof and the wick; of a combined means for feeding the wick and snuffing the same said means including a sprocket for engagement with said wick, a shaft journaled in the burner body and 120 having the sprocket rigidly mounted thereon, a snuffing device located in position adjacent the top of the wick and movable in a direction transversely thereto, and means for rotating said shaft, said means being 125 movable axially relatively to the shaft and operatively connected to the snuffing device.

3. In a hydrocarbon burner, the combination 130 with the body thereof and wick such

- body consisting of a base portion and a cap detachably mounted thereon; of means for snuffing the wick said means including a snuffer mounted within the cap and detachable therewith, and means mounted upon the base portion and operatively connected to the said snuffer for the purpose of actuating the same.
4. In a hydrocarbon burner, the combination with the body thereof and wick such 10 body consisting of a base portion and a cap detachably mounted thereon; of combined means for feeding said wick and snuffing the same said means consisting of a wick feeding shaft mounted upon said base portion and having an axially movable portion, and a snuffing device mounted within said cap and operatively connected to said axially 15 movable portion said device being detachable with the cap.
5. In a hydrocarbon burner the combination with the body thereof and a wick such body comprising a base and a cap detachably mounted upon said base; of means for 20 snuffing said wick said means consisting of a push-rod slidably mounted upon the base, an oscillatory member fulcrumed in said cap and detachable therewith, and interengaging devices on the push-rod and said member respectively whereby movement of the push-rod actuates said member.
6. In a hydrocarbon burner the combination with the body thereof and wick said body comprising a base including a wick 25 tube and a cap the cap having a flame opening; of an oscillatory snuffing device mounted within the cap and consisting of a member of inverted cup form enclosing the upper end of the wick tube and having an elongated opening in vertical alignment with the opening in the cap, and a snuffing strip bridging said opening and constructed and arranged to move across the top of the wick when the member is oscillated, and means 30 yielding maintaining said device in position with the strip to one side of the wick.
7. In a hydrocarbon burner the combination with the body thereof and wick the body comprising a base portion including a wick tube and a cap having a flame opening and detachably mounted upon said base 35 portion; of combined means for feeding said wick and snuffing the same said means comprising an oscillatory device fulcrumed within the cap and detachable therewith; 40 said device consisting of a member of in-
- verted cup form enclosing the upper end of the wick tube and having an opening in vertical alignment with the flame opening in the cap and a snuffing strip bridging said opening, a push rod slidably mounted upon the base portion, interengaging devices mounted respectively upon said push rod and the snuffing device whereby movement of the push rod oscillates said device; a wick 45 feeding shaft journaled in said base portion and extending parallel to said push rod said shaft having an axially movable portion, means operatively connecting said push rod to the axially movable portion, and means 50 yielding maintaining said snuffing device in position with the snuffing strip to one side of the wick.
8. In a hydrocarbon burner the combination with the body thereof and wick the 55 body comprising a base portion including a wick tube and a cap having a flame opening and detachably mounted upon said base portion; of combined means for feeding said wick and snuffing the same said means comprising an oscillatory device fulcrumed within the cap and detachable therewith; 60 said device consisting of a member of inverted cup form enclosing the upper end of the wick tube and having an opening in vertical alignment with the flame opening in the cap and a snuffing strip bridging said opening; a push rod slidably mounted upon the base portion, interengaging devices mounted respectively upon said push rod and the snuffing device whereby movement of the push rod oscillates said device; a wick 65 feeding shaft consisting of a portion fixed against axial movement and journaled in the base of the burner, an axially movable portion in telescopic relation with said fixed portion, means operatively connecting the portions of said shaft together and permitting of relative movement therebetween, means operatively connecting said push rod 70 to the axially movable portion, and a spring encircling the fixed portion of said shaft and maintaining the axially movable portion in position with the snuffing strip located to one side of the wick.
- In testimony whereof I have signed my name to this specification in the presence of two witnesses.

EDWARD C. CORADO.
